LAUNDRY RACK

Walter L. Gill, Redlands, Calif.

Application April 1, 1957, Serial No. 45,522

Term of patent 14 years

(Cl. D49—1)

Fig. 1 is a perspective view of a laundry rack embodying my new design;

Fig. 2 is a side elevational view thereof; and

Fig. 3 is a side elevational view of the rack taken from the left of Fig. 2 and with one of the legs broken away for convenience of illustration only;

Fig. 4 is an enlarged fragmentary perspective view showing the detail of the engaging element at the top of the central support; and

Fig. 5 is an enlarged fragmentary perspective view showing the detail of the engaging element at the bottom of the central support.

I claim:

The ornamental design for a laundry rack, as shown.
